UNITED STATES PATENT OFFICE.

FRANK K. WARD, OF WASHINGTON, DISTRICT OF COLUMBIA.

DESIGN FOR A JAR.

SPECIFICATION forming part of Design No. 21,464, dated April 12, 1892.

Application filed March 10, 1892. Serial No. 424,452. Term of patent 14 years.

To all whom it may concern:

Be it known that I, FRANK K. WARD, a citizen of the United States, residing at Washington, in the District of Columbia, have invented and produced a new and original Design for a Milk or Fruit Preserving Jar, of which the following is a specification.

This design has for its object to provide a novel and ornamental milk or fruit preserving jar, which presents a distinguishing and handsome appearance to the eye, and the leading feature thereof resides in a jar having a breast, a contracted neck, and laterally-projecting lugs arranged on the contracted neck and provided with grooves.

The design is illustrated by the accompanying drawing, in which the figure is a side elevation of a milk or fruit preserving jar illustrating my design.

In the accompanying drawing, the refer-

ence-numeral 1 indicates a glass jar having a breast 2, a contracted tapering neck 3, provided with laterally-projecting lugs 5, having annular grooves 6. The tapering neck is formed at its top portion with a projecting bead 4, formed with an upper beveled surface 7 and a lower beveled or rounded surface 8, which joins the beveled surface 7 and produces an annular approximately sharp edge 9.

What I claim is—

The design for a jar, substantially as shown and described.

In testimony whereof I have hereunto set my hand and affixed my seal in presence of two subscribing witnesses.

F. K. WARD. [L.S.]
